UNITED STATES PATENT OFFICE

169,657

COMBINED BOOK END AND RECEPTACLE

Vivian E. Cravey, Houston, Tex.

Application March 6, 1953, Serial No. 23,937

Term of patent 14 years

(Cl. D33—1)

To all whom it may concern:

Be it known that I, Vivian E. Cravey, a citizen of the United States, residing at Houston, in the county of Harris, in the State of Texas, have invented a new, original, and ornamental Design for a Combined Book End and Receptacle, of which the following is a specification, reference being had to the accompanying drawings, forming a part thereof.

Figure 1 is a front perspective view of a combined book end and receptacle showing my new design; and

I claim:

The ornamental design for a combined book end and receptacle, as shown.

VIVIAN E. CRAVEY.
